BRUSH ELEMENT OF THE STRIP TYPE

Robert W. Vose, West Springfield, Mass., Alfred L. Le Febvre, Windsor, Conn., and Ernest D. Hargreaves, Springfield, Mass., assignors to The Fuller Brush Company, Hartford, Conn., a corporation of Connecticut

Application May 18, 1949, Serial No. 93,942

18 Claims. (Cl. 15—205)

1

The invention relates to a brush element of the strip type wherein the brush fibers are held by a metallic strip and are arranged in longitudinally spaced tufts. While not necessarily so limited, a brush element embodying the invention is particularly adapted for winding on a central core or drum to form a cylindrical brush.

One of the objects of the invention is to provide a brush element of the type specified having the fibers held in longitudinally spaced sockets and having connecting portions between the sockets which are readily bendable so that all bending takes place in the said connecting portions and not at the sockets when the brush element is wound on a core or drum. In accordance with the invention, the readily bendable connecting portions are preferably formed with oppositely inclined rearward diverging parts which are forwardly arched.

A further object of the invention is to provide a brush element having the characteristics as above described and including a generally channel-shaped metallic strip formed to provide the sockets and the connecting portions, the fibers in the several sockets being looped around a longitudinal retaining wire within the channel. The sockets and the connecting portions are so formed that the brush element can be bent at the connecting portions without adversely affecting the sockets.

A still further object of the invention is to provide a brush element as last above-described having means additional to the sockets and adjacent the rear of the channel for preventing the loops of the fibers from moving longitudinally along the wire.

Still other objects of the invention will be apparent from the drawing and from the following specification and claims.

In the drawing we have shown in detail a preferred embodiment of the invention, but it will be understood that various changes may be made from the construction shown, and that the drawing is not to be construed as defining or limiting the scope of the invention, the claims forming a part of this specification being relied upon for that purpose.

Of the drawing:

Fig. 1 is a side view of a brush element embodying the invention, a portion of the brush element being wound upon a drum.

Fig. 2 is an enlarged side view of a short section of the brush element, the portion at the right being in section along the central longitudinal plane.

2

Fig. 3 is a front view with the fibers shown in section along the line 3—3 of Fig. 2.

Fig. 4 is a rear view.

Fig. 5 is a transverse sectional view taken along the line 5—5 of Fig. 3.

Fig. 6 is a transverse sectional view taken along the line 6—6 of Fig. 3.

Fig. 7 is a fragmentary longitudinal sectional view taken along the line 7—7 of Fig. 6.

Fig. 8 is a fragmentary longitudinal sectional view taken along the line 8—8 of Fig. 6.

Fig. 9 is a view similar to Fig. 2 but showing the deformation of the brush element when it is bent to conform to the curvature of a drum such as that shown in Fig. 1.

Fig. 10 is a view similar to Fig. 8 but showing the increased curvature resulting from the deformation of the brush element as shown in Fig. 9.

20 The brush element as shown in Fig. 1 comprises a longitudinal metallic member formed with a plurality of longitudinally spaced similar fiber sockets 10, 10, and also formed with a plurality of similar connecting portions 12, 12 extending between the socket portions 10, 10. Projecting forward from the several sockets 10, 10 are tufts 14, 14 formed of suitable fibers. The term "fibers" is herein used in a generic sense and is intended to include vegetable fibers, or 30 bristles or other animal fibers, or synthetic fibers, or metallic wires, or any other suitable filaments or brush material.

A brush element embodying the invention is particularly adapted for bending or winding to 35 provide a circular or cylindrical external shape. The brush element may be wound on a central core or drum such as the drum 16 as shown in Fig. 1, the said element being ordinarily wound helically on the drum to form a cylindrical brush.

40 The brush strip is substantially weaker at the connecting portions 12, 12 than at the sockets 10, 10, so as to facilitate bending at the connecting portions rather than at the sockets. Preferably and as shown, the sockets 10, 10 have a substantial depth from front to rear, and the connecting portions 12, 12 between the socket portions 10, 10 have relatively small depth and in any event have a depth substantially less than the depth of the sockets. Inasmuch as the connecting portions 12, 12 have relatively small depth or are otherwise 45 weak, all bending takes place in the said connecting portions thus avoiding any deformation of the socket portions 10, 10.

50 While the invention is not necessarily so limited, the before-mentioned metallic member is

preferably a channel-shaped metallic strip having a rear wall 18 and having two similar opposite side walls 20, 20. The side walls 20, 20 include longitudinally spaced contacting central sections 22, 22 and longitudinally spaced oppositely disposed concave socket sections 24, 24 between the central sections. Each two oppositely disposed socket sections 24, 24 cooperate to provide an entirely closed socket in which the fiber tufts 14, 14 are positioned, the tufts projecting forward from the sockets as already stated.

Between the socket sections 14, 14, the side walls of the channel comprise transversely extending parts 26, 26 constituting socket connecting portions, these parts being preferably located approximately midway between the front of the channel and the rear wall thereof. Preferably, the parts 26, 26 of the side walls are oppositely inclined and diverge in the rearward direction.

The centrally located sections 22, 22 of the side walls are formed with notches 28, 28 which extend rearward to the inner front edges of the said oppositely inclined parts 26, 26. Openings 30, 30 are provided at the rear, these openings interrupting the rear wall 18 and interrupting the rear portions of the side walls 20, 20. These openings 30, 30 extend forward to the outer rear edges of the oppositely inclined parts 26, 26. It will be seen that, by reason of the notches 28, 28 at the front and the openings 30, 30 at the rear, the said parts 26, 26 constitute the sole connections between the socket portions of the strip. These connecting parts 26, 26 are relatively thin and they can be readily bent rearwardly, as for instance when the brush element is wound on a drum as shown in Fig. 1. While it is essential that bending shall occur only at the connecting portions of the strip, it is desirable to avoid excessive flexibility and this is brought about by placing the connecting parts 26, 26 in oppositely inclined positions as shown, the said parts diverging in the rearward direction.

The oppositely inclined connecting parts 26, 26 are preferably longitudinally arched at 32, 32 as clearly shown in Figs. 7 and 8. There is little or no arching at the inner edges of the said parts, but the extent of arching progressively increases from the inner edges thereof to the outer edges thereof. For a reason to be hereinafter set forth, the arching is preferably in forward directions.

A longitudinal core or retaining wire 34 is preferably provided, this wire being within the channel, and in front of the interrupted rear wall 18 and behind the inner zones of the oppositely inclined connecting parts 26, 26. The bunches of fibers constituting the several tufts 14, 14 are looped around the wire 34 as clearly shown in Figs. 2 and 5, the wire thus serving to retain the fibers in place. The number of fibers in each bunch is such that the corresponding socket is completely filled. Thus the sockets and the rear wall cooperate with the retaining wire to firmly support the fibers. The wire engages the connecting parts 26, 26 and these parts serve not only to prevent forward movement of the wire but also to hold the wire in central position. Inasmuch as the parts 26, 26 are arched in the forward directions, the arching does not in any way affect the wire 34.

During brushing action there is a tendency for the fibers to move inward in their respective sockets, the result being that the inner looped portions of the bunches of fibers tend to move longitudinally along the wire. Means additional

to the sockets are provided which are so positioned as to prevent any longitudinal movement of the looped portions of the fibers. This means may be variously formed, but preferably and as shown it comprises centrally located tabs 36, 36 projecting forward from the rear wall. There are two tabs 36, 36 at opposite sides of each fiber loop as clearly shown in the right portion of Fig. 2. Thus the looped portions of the fibers are closely held and confined by the rear wall 18 and by the tabs 36, 36.

When the rear wall 18 is interrupted by openings such as 30, 30, the tabs 36, 36 are formed at the edges of the openings. The tabs 36, 36 preferably engage the wire 34 at the rear thereof, the wire being thus firmly held between the tabs and the connecting parts 26, 26.

Fig. 9 is similar to Fig. 2 but shows the brush element bent to conform to a curvature 20 such as that of the drum 16. All bending has taken place at the connecting parts 26, 26 and bending has been facilitated by the arching of the said parts at 32, 32. During bending the inner forward portions of the parts 32, 32 are under tension and the outer rear portions of the said parts are under compression. There is little or no arching at the portions under tension but there is substantial arching at the portions under compression. The arched compression portions yield during bending, the arching being increased as will be observed by comparing Fig. 10 with Fig. 8. Inasmuch as the outer compression portions freely yield, there is no stretching of the inner tension portions, and there is therefore no tendency to distort or open the sockets.

Preferably the centers of bending of the parts 26, 26 are spaced from the rear wall 18 at least as far as is the center of the wire 34, and the centers of bending may advantageously be spaced 40 slightly forward of the center of the wire. Thus when the brush element is bent as shown in Fig. 9, there is no tendency to stretch the wire 34. If the centers of bending were at the rear of the center of the wire, there would be a tendency to stretch the wire during bending and bending would be resisted by the resulting tension in the wire.

While reference has been made particularly to rearward bending of the brush element as shown in Fig. 9, the strip is also adapted for lateral bending in a direction parallel with the rear wall 12. When lateral bending takes place, one connecting part 26 is under tension and the opposite connecting part 26 is under compression. In the part under tension the arching at 28 is reduced, and in the part under compression the arching at 28 is increased.

What we claim is:

1. A brush element of the strip type comprising in combination, a single longitudinal sheet metal member of substantially uniform thickness bent to provide a rear wall and to provide two similar oppositely disposed side walls which side walls are shaped to form a plurality of longitudinally spaced similar fiber sockets each having substantial depth from front to rear and which side walls are also shaped to form a plurality of similar connecting portions extending longitudinally between the sockets, each connecting portion having a depth substantially less than the depth of the sockets and each connecting portion consisting solely of two oppositely inclined rearward diverging parts which are spaced rearward from the fronts of the sockets 75 and which are readily bendable, and tufts of

fibers in the several sockets and projecting forward therefrom.

2. A brush element as set forth in claim 1, wherein the oppositely inclined rearward diverging connecting parts are longitudinally arched to facilitate bending.

3. A brush element as set forth in claim 1, wherein the oppositely inclined rearward diverging connecting parts are longitudinally arched to facilitate bending with the extent of arching progressively increasing from the centers of the connecting portions toward the sides thereof.

4. A brush element of the strip type comprising in combination, a longitudinal sheet metal strip bent to provide a rear wall and having two similar opposite side walls which side walls include portions perpendicular to the rear wall and formed with longitudinally spaced similar concave socket sections cooperating with each other to provide fiber sockets and which side walls are formed with longitudinal connecting portions extending between the socket sections, the said strip having longitudinally spaced openings at the rear which are between the sockets and which interrupt the rear wall and the rear parts of the side walls to provide separate longitudinally spaced rear wall portions behind the respective sockets so that upon rearward bending of the strip all bending takes place in the said connecting portions of the side walls, and tufts of fibers in the several sockets and projecting forward therefrom.

5. A brush element as set forth in claim 4, wherein the connecting portions of the side walls include transversely extending parts spaced rearward from the fronts of the side walls.

6. A brush element as set forth in claim 4, wherein the connecting portions of the side walls are transversely extending parts spaced rearward from the fronts of the side walls, wherein the side walls are provided between the sockets with notches which extend rearward substantially to the said transversely extending parts, and wherein the openings at the rear extend forward substantially to the said transversely extending parts.

7. A brush element as set forth in claim 4, wherein the connecting portions of the side walls are oppositely inclined rearward diverging parts spaced rearward from the fronts of the side walls, wherein the side walls are provided between the sockets with notches which extend rearward substantially to the forward edges of the said rearward diverging parts, and wherein the openings at the rear extend forward substantially to the rearward edges of the said rearward diverging parts.

8. A brush element of the strip type comprising in combination, a longitudinal metallic member formed with a plurality of longitudinally spaced similar fiber sockets each having substantial depth from front to rear and also formed with a plurality of similar connecting portions extending between the sockets, each connecting portion comprising two oppositely inclined rearward diverging relatively thin parts which are spaced rearward from the fronts of the sockets and which are readily bendable, a single longitudinal wire behind the forward portions of the several sockets and engaging the several oppositely inclined connecting parts, and tufts of fibers looped around the wire and projecting through the sockets and forward therefrom.

9. A brush element as set forth in claim 8, wherein the oppositely inclined rearward diverg-

ing connecting parts are longitudinally arched to facilitate bending, the said parts being arched in forward directions.

10. A brush element of the strip type comprising in combination, a longitudinal sheet metal strip bent to provide a rear wall and having two similar opposite side walls which side walls include portions perpendicular to the rear wall and formed with longitudinally spaced similar concave socket sections cooperating with each other to provide fiber sockets and which side walls are formed with longitudinal connecting portions extending between the socket sections and having transversely extending parts, the said strip having longitudinally spaced openings at the rear which are between the sockets and which interrupt the rear wall and the rear parts of the side walls to provide separate longitudinally spaced rear wall portions behind the respective sockets so that upon rearward bending of the strip all bending takes place in the said connecting portions of the side walls, a longitudinal wire in front of the said spaced rear wall portions and behind the inner zones of the transversely extending parts of the connecting portions, and tufts of fibers looped around the wire and projecting through the sockets and forward therefrom.

11. A brush element as set forth in claim 10, wherein the side walls are provided between the sockets with notches which extend rearward substantially to the said transversely extending parts, and wherein the openings at the rear extend forward substantially to the said transversely extending parts.

12. A brush element of the strip type comprising in combination, a longitudinal metallic strip having a rear wall and having two similar opposite side walls which side walls include portions perpendicular to the rear wall and formed with longitudinally spaced similar concave socket sections cooperating with each other to provide fiber sockets and which side walls are formed with longitudinal connecting portions extending between the socket sections and comprising oppositely inclined rearward diverging parts, the said strip having notches between the sockets which extend rearward substantially to the said rearward diverging parts and the said strip having longitudinally spaced openings at the rear which are between the sockets and which interrupt the rear wall and the parts of the side walls at the rear of the rearward diverging parts so that upon rearward bending of the strip all bending takes place in the said rearward diverging parts, a longitudinal wire in front of the said spaced rear wall portions and contacting with the said rearward diverging parts at the rear thereof, and tufts of fibers looped around the wire and projecting through the sockets and forward therefrom.

13. A brush element as set forth in claim 12, wherein the center of bending of the rearward diverging connecting parts is spaced from the rear wall at least as far as is the center of the wire.

14. A brush element of the strip type comprising in combination, a longitudinal metallic strip having a rear wall and having two similar opposite side walls formed to provide a plurality of longitudinally spaced fiber sockets, a single longitudinal substantially straight wire in front of the rear wall and behind the forward portions of all of the sockets, bunches of fibers looped around

the wire and projecting through the respective sockets and forward therefrom to form tufts, and means for preventing the looped portions of the said bunches of fibers from moving longitudinally with respect to the wire, the said means being integral with the strip and additional to the sockets and the said means being adjacent and at the edges of the looped portions of the respective bunches of fibers.

15. A brush element of the strip type comprising in combination, a longitudinal metallic strip having a rear wall and having two similar opposite side walls formed to provide a plurality of longitudinally spaced fiber sockets, a single longitudinal wire in front of the rear wall and behind the forward portions of all of the sockets, bunches of fibers looped around the wire and projecting through the respective sockets and forward therefrom to form tufts, and forward projecting tabs on the rear wall adjacent and at the edges of the looped portions of the respective bunches of fibers for preventing the said looped portions from moving longitudinally with respect to the wire.

16. A brush element of the strip type comprising in combination, a longitudinal metallic strip having a rear wall and having two similar opposite side walls which side walls include portions perpendicular to the rear wall and formed with a plurality of longitudinally spaced similar concave socket sections cooperating with each other to provide fiber sockets and which side walls are formed with longitudinal connecting portions extending between the socket section and having transversely extending parts, a single longitudinal wire in front of the rear wall and behind the inner zones of the transversely extending parts of all of the connecting portions, bunches of fibers looped around the wire and projecting through the respective sockets and forward therefrom to form tufts, and means adjacent the looped portions of the respective bunches of fibers and additional to the sockets for preventing the said looped portions of the respective bunches of fibers from moving longitudinally with respect to the wire, the said means being integral with the strip and additional to the sockets and the said means being adjacent and at the edges of the looped portions of the respective bunches of fibers.

17. A brush element of the strip type comprising in combination, a longitudinal metallic strip having a rear wall and having two similar opposite side walls which side walls include portions perpendicular to the rear wall and formed with a plurality of longitudinally spaced similar concave socket sections cooperating with each other to provide fiber sockets and which side walls are formed with longitudinal connecting portions extending between the socket sections and having transversely extending parts, the rear wall of the said strip having longitudinally spaced pairs of forward projecting tabs with the tabs

of each pair adjacent the edges of the corresponding socket, a single longitudinal wire behind the inner zones of the transversely extending parts of all of the connecting portions and in front of all of the said forward projecting tabs, and bunches of fibers looped around the wire and projecting through the sockets and forward therefrom to constitute tufts, the inner looped portion of each bunch of fibers being between the tabs of the corresponding pair so that the tabs prevent longitudinal movement of the fibers with respect to the wire.

18. A brush element of the strip type comprising in combination, a longitudinal metallic strip having a rear wall and having two similar opposite side walls which side walls include portions perpendicular to the rear wall and formed with a plurality of longitudinally spaced similar concave socket sections cooperating with each other to provide fiber sockets and which side walls are formed with longitudinal connecting portions extending between the socket sections and having transversely extending parts, the said strip having longitudinally spaced openings at the rear which are between the sockets and which interrupt the rear wall and the rear parts of the side walls to provide separate longitudinally spaced rear wall portions behind the respective sockets so that upon rearward bending of the strip all bending takes place in the said connecting portions of the side walls and the said strip being formed with pairs of forward projecting tabs at the ends of the said longitudinally spaced openings, a single longitudinal wire behind the inner zones of the transversely extending parts of all of the connecting portions and in front of all of the said forward projecting tabs, and bunches of fibers looped around the wire and projecting through the sockets and forward therefrom to constitute tufts, the inner looped portion of each bunch of fibers being between the tabs of the corresponding pair so that the tabs prevent longitudinal movement of the fibers with respect to the wire.
